MIXING METHOD AND APPARATUS

George W. Newton, Baltimore, Md., assignor to
 Crown Cork & Seal Company, Inc., Baltimore,
 Md., a corporation of New York

Original application July 5, 1939, Serial No.
 282,871. Divided and this application August
 30, 1940, Serial No. 354,881

3 Claims. (Cl. 259—54)

The present invention relates to a mixing apparatus and method and, more particularly, to an apparatus and method for mixing beverages such as "soft drinks" in the individual containers in which they are sold.

This application is a division of my application for Mixing apparatus and method, Serial No. 282,871, filed July 5, 1939, now Patent No. 2,216,090, issued Sept. 24, 1940.

In the bottling of carbonated beverages, it is usual to first flow a quantity of syrup into the bottle or other container, and to then fill the remainder of the container with carbonated water. Machines have heretofore been developed and used for mixing the relatively heavy syrup with the upper strata of carbonated water. However, such prior machines are not altogether satisfactory under certain conditions, due to the fact that the bottles are moved somewhat too vigorously during the mixing process, with the result that foaming of the contents occurs and continues for some moments after the mixing action is completed.

The particular condition under which such foaming is most objectionable is in plants where light sensitive inspecting mechanisms are used to scan the bottle for the purpose of ascertaining whether any foreign matter is present in its contents. One widely used inspection machine rotates the bottles, and then holds it against rotation as its contents continue to rotate, and while the bottle is moving past a photoelectric cell. By this arrangement the entire contents of the bottle are slowly swirled in front of the photoelectric cell. In order to be completely effective in detecting extremely small fragments of foreign matter in the bottle contents, the inspection mechanism must be so sensitive to the passage of light through the bottle that it will respond to the differences in light transmission resulting from the movement of foam bubbles through the beverage and may discard such bottles, causing an entirely unnecessary waste. More particularly, foam bubbles in the liquid cause the inspection machine to reject the bottle and foam bubbles which collect on the upper surface of the liquid in the bottle are drawn down into the vortex or meniscus that is formed by the liquid, making it impossible to properly inspect for floating particles of foreign matter.

An important object of the present invention is to provide a mixing apparatus and method which will thoroughly mix the contents of a container and, more particularly, will thoroughly mix all syrup in a carbonated beverage con-

tainer with the carbonated water without undesirable and continuing foaming of the contents.

Another object of the present invention is to minimize the possibilities of foaming of a carbonated beverage during a mixing operation.

It has been found that a basic reason for the flow of bubbles through the liquid during mixing is the fact that the head space of the sealed container is filled with air or gas at substantially atmospheric pressure while the liquid contents contain gas in solution and under a much higher pressure. When the container is bodily moved during the mixing process, the gas in solution immediately moves to the low pressure area, and as this area moves about in the bottle due to the movement of the bottle, the foam bubbles go through a marked movement. Such movement, as indicated above, may continue until sometime after bodily movement of the bottle has ceased and may thereby affect the inspection machine.

The present invention contemplates creating a pressure condition in the container head space as by agitating the container contents prior to tilting or inverting. This agitation is preferably effected by tapping the bottle or subjecting it to a blow of sufficient force to cause gas in solution in the liquid to rise into the container head space so that this space, previously filled with air or gas at atmospheric pressure, will be filled with gas at substantially the same pressure as that of the gas in solution. Such agitation of the bottle contents must be performed after the container has been sealed and the most satisfactory results are obtained by performing this agitating step a few moments prior to the mixing operation. For example, the agitation to cause rise of gas into the container head space can be performed immediately after the bottle has been sealed, and while at least the upper portion of the water in the bottle is free of syrup and hence has a low surface tension, so that gas will have a full opportunity to quickly rise from the bottle contents prior to such bodily movement of the bottle as will cause flow of its contents within the bottle.

The agitation of the container contents referred to above may obviously be used with mixing methods and apparatus other than those disclosed in the present application.

Other objects and advantages of the invention will be apparent from the following specification and drawings, wherein:

Figure 1 is a plan view of the outfeed portion of a filling machine and a portion of a mixing machine constructed in accordance with the

present invention. In this view the super-structures of the two machines are omitted.

Figure 2 is a vertical central sectional view through the mixing apparatus on a line extending from front to rear of the machine, and

Figure 3 is a detail vertical sectional view on the line 3—3 of Figure 1.

Referring to Figure 1, the numeral 136 designates the outfeed portion of a beverage filling machine including the usual transfer dial 110 which moves filled bottles B containing a lower layer of syrup and an upper body of carbonated water from a rotary filling table, not shown, to the dial 260 which is beneath and associated with the crowning mechanism of the filling machine. After the bottles have been crowned and thereby sealed, they are engaged by the usual outfeed dial 135 which moves them to the straight-line outfeed conveyor 135a of the filling machine. From this conveyor they move to the infeed conveyor 144 of the mixing apparatus 120.

Mixing apparatus 120 is of the type disclosed in my above-mentioned original application, Serial No. 282,871. Such mixing apparatus may be generally described in connection with Figure 2 as comprising a stationary base portion 121 having a fixed post 122 extending upwardly from its rearward portion and on which a table 123 is mounted for rotation by any suitable drive means. Table 123 is provided with a plurality of upstanding housings 124 spaced about its periphery and having horizontal shafts 125 journaled in their upper ends. Each shaft 125 carries a container supporting element or device 126 including a base portion 176 having a bottle platform 132 rotatable therein. Each element 126 also includes a reciprocable upper and clamping arm or head 198 having a rotatable portion adapted to engage the cap of the container so that the clamped container can rotate with platform 132. The shafts 125 are adapted to be rotated to move the elements 126 radially of table 123, all as described in said original application.

As a container supporting element 126 rotates past the stationary front table 120a, a bottle will be placed upon the platform 132 of that container support as shown at the left of Figure 2 by an infeed dial 141 which has received the bottle from the infeed conveyor 144.

As is fully disclosed in said original application, the clamping head 198 of the bottle support 126 will be raised during the insertion of the bottle but will immediately descend to firmly clamp the bottle upon the bottle platform 132. Subsequently, the bottle will be turned to the inverted position shown at the right of Figure 2 so that the bottle platform 132 which is rotatable in the supporting element 126 will contact with a continuously moving belt 133 driven by a motor assembly 226, belt 133 being mounted to pass about a wheel 224 journaled on the upper portion of post 122. As a result, the bottle will be spun while inverted and while the rotary table 123 is moving through approximately half a revolution. Before the bottle supporting element 126 again approaches the front table 120a, the supporting element 126 will be turned radially with shaft 125 to restore the bottle to upright position, the clamping arm 198 will lift to the position shown at the left of Figure 2, and the bottle will be removed from the bottle supporting platform 132 by the outfeed dial 142.

As best shown in Figures 1 and 3, a tapping arm 134 is secured in a collar 250 which is rotatable upon a stud 251 secured in the guide plate

252 which surrounds the outfeed dial 135 of the filling machine 136. A coil spring 253 has its upper end secured in the underside of the collar 250, while its lower end is fixed in the lower and headed end 254 of the stationary stud 251. The tapping arm 134 extends through a slot 255 formed in the depending skirt 256 of the guide plate 252 so that its outer end is in the path of movement of bottles moving about the outfeed dial 135. In operation, a bottle moving in one of the pockets of the outfeed dial 135 will swing the tapping arm 134 against the action of spring 253 from the solid line position of Figure 1 to the dotted line position of the same view. When the bottle has then moved past the end of the tapping arm, the latter will be swung backwardly by the spring 253 to strike the succeeding bottle so as to agitate the contents of the bottle and cause gas to be released from the carbonated liquid therein and to rise into the head space to create a pressure condition within the head space approximating the pressure of the gas in solution in the carbonated liquid.

The tension of the spring 253 may be adjusted by rotating the stud 251 and locking it in adjusted position by the lock nut illustrated in Figure 3.

The position of the tapping arm 134 may be varied from that illustrated in Figure 1, that is, the tapping arm may be positioned at a point closer to the crowning mechanism dial 260, or it may be placed at some point closer to the mixing apparatus. However, the tapping arm 134 should be positioned at a sufficient distance in advance of the mixing apparatus that the rise of gas resulting from agitation of the bottle contents by the tapping arm will be completed prior to the movement of the bottle onto a bottle supporting platform 126 of the mixing apparatus.

As has been stated above, the tapping operation just described is of considerable efficacy in preventing undue foaming of a carbonated liquid during the bodily movement of a bottle which occurs during a mixing process because, as hereinbefore stated, it increases the pressure in the container head space, and thereby minimizes the rise of foam bubbles during the mixing operation, and further insures that there will be no continuing rising of foam bubbles occurring during the movement of the bottle through an inspection machine.

It will be observed that by the above structure and method the contents of a bottle will be agitated and the head space pressure increased before mixing by bodily movement of the container. Obviously, the mixer which can be used adjacent the tapping mechanism is not limited to that disclosed in the drawings.

It will be understood that the terminology used in the specification is for the purpose of description alone, the scope of the invention being indicated by the claims.

I claim:

1. The method of mixing the contents of a closed container having therein a lower strata of syrup, a superposed body of carbonated water and with the headspace filled with a gaseous fluid at substantially atmospheric pressure, comprising subjecting the container to a blow while the latter is upright and the syrup is not mingled with the upper portion of the body of water so that the surface tension of the water is at a minimum, the blow being of sufficient force to cause a portion of the gas in the carbonated

water to bubble to the surface of the water to establish a higher pressure in the container headspace.

2. The method of mixing the contents of a closed container having therein a lower strata of syrup, a superposed body of carbonated water and with the headspace filled with a gaseous fluid at substantially atmospheric pressure, comprising subjecting the container to a blow while the latter is upright and the syrup is not mingled with the upper portion of the body of water so that the surface tension of the water is at a minimum, the blow being of sufficient force to cause a portion of the gas in the carbonated water to bubble to the surface of the water to establish a higher pressure in the container headspace, and then bodily moving the container to mix the syrup and water after the headspace pressure has been increased so that bubbling of gas through the mixture during such bodily movement will be minimized.

3. In combination, means to fill a container with a lower layer of syrup and a superposed body of carbonated water with the upper portion of the water free of syrup to have a low surface tension, means to seal the container in the open atmosphere so that its headspace will contain a gaseous fluid at substantially atmospheric pressure, means to impart a blow to the container while in the above described condition, the blow being of sufficient force to cause gas to rise from the carbonated water and into the container headspace to establish a higher pressure in the headspace while the surface tension of the upper portion of the liquid contents is low, and means to bodily move the container to mix the syrup and water after the headspace pressure has thus been increased so that bubbling of gas during such bodily movement will be minimized.

GEORGE W. NEWTON.
